UNITED STATES PATENT OFFICE.

ARTHUR A. ANDREWS, OF ROCKFORD, ILLINOIS, ASSIGNOR OF ONE-HALF TO JULIUS G. WEINBERG, OF ROCKFORD, ILLINOIS.

STREET-SWEEPING MACHINE.

1,121,059.

Specification of Letters Patent. Patented Dec. 15, 1914.

Application filed June 8, 1914. Serial No. 843,745.

To all whom it may concern:

Be it known that I, ARTHUR A. ANDREWS, a citizen of the United States, residing at Rockford, in the county of Winnebago and 5 State of Illinois, have invented certain new and useful Improvements in Street-Sweeping Machines, of which the following is a specification.

This invention pertains to street-sweeping machines of that type adapted to be manually operated, that is, pushed by an operator along a street pavement to clean the surface thereof of loose dust, dirt, etc.

The purpose of my invention primarily, 15 is to provide a street-sweeping machine of the above character having sweeping and elevating conveyer means, with improved driving means, for the purpose of simplifying the construction of the machine and to 20 permit the machine to be light of draft.

Another object of my invention is to provide a sweeping machine of this type with sweeping and elevating conveyer means so arranged that the sweeper will gather dirt 25 and throw it forwardly toward the conveyer to be elevated thereby and discharged into a receptacle carried by the machine.

A further object of my invention is to provide a sweeping machine mounted upon 30 a pair of carrying-wheels, with sweeping means, elevating conveyer means, and a detachable dirt receptacle, so arranged relatively to the carrying-wheels as to effect a very compact machine and one in which the 35 several devices above named are evenly balanced relatively to the carrying-wheels.

A further object is to provide a street-sweeping machine with a novel means for mounting and detaching a dirt receptacle.

Another object is to equip the machine 40 with wheel-means auxiliary to the carrying-wheels for maintaining the sweeping brush in a determined relation with the ground and whereby the sweeping brush 45 may be moved through bodily movement of the machine frame, to an inoperative position without moving the said wheel-means from the ground.

Referring to the drawings—Figure 1 is 50 a longitudinal vertical sectional view through my improved street-sweeping machine, taken on the line 1—1 of Fig. 2, a portion of the lower dirt casing and of the conveyer being shown in section. Fig. 2 is 55 a plan view of the sweeping machine with

portions of the hood broken away. Fig. 3 is a detail sectional view taken on the line 3—3 of Fig. 1, illustrating the clutch lever. Fig. 4 is a plan sectional view taken on the line 4—4 of Fig. 1. Fig. 5 is a transverse 60 sectional view through the machine along the wheel axle, taken on the line 5—5 of Fig. 1. Fig. 6 is a detail vertical sectional view through one of the caster-wheel supports; and Fig. 7 is a detail sectional view 65 taken on the line 6—6 of Fig. 5.

The sweeping machine comprises in general, a main frame carried by a pair of wheels, the frame carrying the sweeping apparatus and parts auxiliary thereto, and 70 is formed of upper longitudinal side-bars 8, a lower U-shaped bar 9, forward and rear vertically disposed bars 11 and 12 respectively, connecting the upper and lower frame bars, and inclined brace bars 13 and 75 14. This particular arrangement of frame is not essential, as it is obvious that various mechanically equivalent structures may be devised to produce a frame suitable for the sweeping means.

The frame is carried primarily, by a pair of wheels 15 of relatively large diameter, the wheels being mounted loosely upon an axle 16 which is journaled on the frame through bearings 17. The wheels are each provided with a ratchet connection 10 with the axle, of suitable construction, so that the axle will rotate with the wheels upon movement of the same forwardly over the ground, but will be disengaged therefrom when the 80 movement of the wheels is reversed.

Mounted loosely upon the axle 16 is a sleeve 18 with one end thereof journaled in one of the bearings 17. A pair of sprocket-wheels 19 are fixedly mounted on sleeve 18; and the sleeve is driven from the wheels 15 through the intermediary of a clutch 21 of suitable construction, the clutch being operable to engage and disengage the shaft with the sleeve, by means of a hand lever 22 located at the rear of the frame.

An endless elevating conveyer designated generally by the reference character 23 is arranged to circumscribe the axle 16 and is mounted upon sprocket-wheels positioned 105 at the upper and lower portions of the machine frame in such a manner that the elevating side of the conveyer extends from a point in proximity with the ground at the rear of the wheels' axis, to an elevated point 110

forward of said axis. The elevating conveyer comprises, more particularly, an endless flexible body 24 upon which is mounted a plurality of buckets 25, and is equipped at 5 its sides with sprocket-chains 26 and 27. The upper and lower sprocket-wheels 28 and 29 respectively, mounted upon the frame, mesh with the conveyer sprocket-chains and 10 guide the conveyer in the path above mentioned. Both the elevating and return sides of the conveyer chain portions are in mesh with the sprocket-wheels 19, whereby upon driving of the sleeve 18 from the carrying-wheels the elevator is operated.

15 Mounted upon and intermediate the sides of the lower frame bar 9, at the rear of the conveyer, is a shaft 31 carrying a sweeping brush 32. The space intermediate the brush and lower end of the conveyer is inclosed 20 by a casing 33, thus providing an inclosed passage for guiding dust, dirt, etc. from the brush to the conveyer.

25 The brush is rotated through means of a sprocket-chain connection 34 driven from the conveyer sprocket-chain, the chain 34 being mounted upon sprocket-wheels 35 and 36, the latter carried by a shaft 37 adjustably mounted on a frame-connected bracket 38, and a sprocket-wheel 39 mounted on said 30 shaft 37 being in mesh with the conveyer sprocket-chain.

35 At the rear lower end of the frame is a pair of caster-wheels 41 mounted in sleeve-casings 42. The pivot shanks of the caster-wheels have adjusting nuts 43 on their lower ends, which nuts abut the bottom ends of the casings 42 and are adjustable vertically. This construction maintains the sweeping brush in a determined relation to the ground, and 40 permits the brush to be adjusted relatively thereto by adjusting the nuts 43. The upper end of the caster-wheel shank is provided with an annular groove 44; and carried by the casing 42 below the groove 44 is a laterally extending detent finger 45 spring-pressed against the shank, so that when the shank is lowered relatively to the frame to 45 raise the brush from the ground, the detent finger will enter said groove and hold the sweeping brush elevated, subject to be lowered by manually withdrawing the detent finger.

50 A dirt receptacle 46 open at its top and upper rear end is detachably mounted upon the forward end of the frame in such position as to receive the discharge from the upper end of the conveyer. The receptacle is so mounted by means comprising downwardly pointed lugs 47 fixed to each side of 55 the receptacle, the lugs resting upon brackets 48 shaped to receive the pointed ends thereof, and levers 49 pivoted intermediate their ends, shaped to engage the pointed ends of the lugs and to lift and guide, upon moving 60 the forward ends of the levers downwardly,

the receptacle from its operative position to a position forward and removed therefrom, whereby the receptacle may be easily removed. A hood 51 covers the top of the machine and is connected by a hinge at its forward end to a cover 52 for the top of the dirt receptacle. A handle 53 at the rear end of the frame provides means for the operator to grasp when pushing the sweeping machine.

75 The drawings illustrate the machine operative and ready for sweeping. Upon pushing the machine forwardly the elevating conveyer will be driven by the wheels 15, through sprockets 19, so that the conveyer at 80 the rear side of the machine will travel upwardly, in the same direction, comparatively, with the rotation of the wheels. But the brush, by reason of its sprocket connection or reverse drive connection with the conveyer sprocket-chain, will be rotated in a direction opposite to that of the wheels and conveyer, whereby the brush will gather loose dirt from the pavement and throw it forwardly through casing 33 onto and to be 85 gathered by the conveyer, which will elevate and discharge it into the receptacle 16. It will be seen that dirt which should happen to be dropped by the return side of the conveyer or from the receiving end thereof, 90 would be gathered by the brush because the brush is at the rear of such places as dirt leakage is apt to occur.

95 The mechanical embodiment of my invention herein shown and described illustrates 100 the object of my invention; and I do not desire to be restricted by the mechanical details of construction shown, but believe that my invention should be circumscribed only by the scope of the appended claims, and 105 that all modifications which fall within the terms of these claims should be considered as part of this invention.

110 I claim as my invention:

1. In a street-sweeping machine, the combination of a receptacle, a combined elevating conveyer and sprocket-chain, the conveyer arranged to discharge into the receptacle, a rotary brush adjacent the ground at the rear of the conveyer, and a sprocket 115 wheel and chain connection between the conveyer sprocket-chain and the brush for driving the brush in the direction opposite to that of the conveyer, whereby dirt gathered by the brush will be thrown forward 120 onto the conveyer.

125 2. A sweeping machine comprising, a pair of wheels and an axle therefor, a frame mounted upon the axle, a sprocket-wheel coaxial with the axle and rotatable with one of the wheels, an endless elevating conveyer having a sprocket-chain in mesh with said sprocket-wheel, the conveyer extending above and below the said axle, a receptacle into which the upper end of the conveyer is 130

- adapted to discharge, a rotary sweeping brush in proximity with the ground at the rear of the wheel axle, and a sprocket-wheel in mesh with the conveyer sprocket-chain 5 and having a driving connection with the brush to rotate the same in the direction opposite to that of the wheels, the brush being adapted to gather dirt and throw it forwardly to the elevating conveyer.
- 10 3. In a street-sweeping machine, the combination of an endless vertically disposed elevating conveyer, a sprocket-chain mounted co-axially with the conveyer, a rotary sweeping brush at the rear of the conveyer 15 adapted to gather dirt and throw it forward to the conveyer, a sprocket-wheel connected with the brush, a sprocket-wheel meshing with said sprocket-chain, and an endless chain connecting the said brush sprocket-wheel with the conveyer sprocket-wheel.
4. In a street sweeping machine, the combination of a pair of supporting-wheels, an axle upon which the wheels are journaled, a sprocket-wheel mounted on the axle to 25 rotate with one of the wheels, a sprocket-chain and elevating conveyer connected to move together and being coaxially mounted on one axis above and one below the axle, the sprocket-chain being in mesh intermediate said spaced axis with said sprocket-wheel, a receptacle positioned to receive the discharge from the upper end of the conveyer, a rotary brush positioned in proximity to the ground and to the rear of the 30 lower end of the conveyer for gathering dirt and throwing it forward onto said conveyer, and means for rotating the brush.
5. In a street sweeping machine, the combination of supporting-wheels and an axle 35 therefor, a driving sprocket-wheel mounted coaxially with the wheels to rotate therewith, a pair of sprocket-wheels one mounted above and the other below the axle, an elevating conveyer coaxially mounted with the 40 upper and lower sprocket-wheels and connected with the same to be driven thereby, a sprocket-chain mounted to run on said pair of sprocket-wheels and being in mesh intermediate said wheels with the said driving sprocket-wheel, dirt gathering means 45 located in proximity to the ground for delivering dirt gathered thereby to the lower portion of the elevating conveyer, and means for receiving the discharge of the 50 dirt from the upper end of said conveyer.
6. In a street sweeping machine, the combination of supporting-wheels and an axle therefor, a sprocket-wheel mounted coaxially with the axle to rotate with one of the 55 wheels, and a sprocket-chain and an elevating conveyer connected together and be-
- ing coaxially mounted on axes spaced above and below the axle, the chain being in mesh intermediate said spaced axes with said sprocket-wheel to be driven thereby. 65
7. In a street sweeping machine, the combination of supporting-wheels and an axle therefor, a sprocket-wheel coaxially mounted with the axle and connected with one of the wheels to be rotated thereby, and an 70 elevating conveyer extending from proximity to the ground to an elevated position, a rotary brush located at the rear of the conveyer adapted to gather dirt and throw it forward to be carried by the conveyer to 75 an elevated point, a sprocket-chain meshing with said sprocket-wheel and connected with the elevating conveyer for operating the same, and a driving connection between said sprocket-chain and the rotary brush for 80 operating the same comprising a pair of sprocket-wheels coaxially mounted, one being in mesh with the said sprocket-chain and the other having a sprocket-chain connection with the rotary brush. 85
8. In a street sweeping machine, the combination of supporting-wheels and an axle therefor, a pair of sprocket-wheels one mounted above and the other below the axle, a sprocket-chain in mesh with said sprocket-wheels and having a driving connection with one of the supporting-wheels, an elevating conveyer connected to and mounted coaxially with the sprocket-chain, a rotary brush mounted in proximity to the ground 90 and adapted to gather dirt to be elevated by the conveyer, and a sprocket-wheel meshing with said sprocket-chain and having a driving-connection with the rotary brush for 95 rotating the same. 100
9. In a street sweeping machine, the combination of a pair of supporting-wheels, a frame mounted thereon, a rotary sweeping brush mounted on the frame at the rear of the wheel's axis, an elevating conveyer disposed forward of the brush and adapted to receive dirt gathered thereby, a caster wheel connected to a vertically disposed pivot member mounted on the frame at the rear of the wheel's axis and being vertically adjustable with respect to the frame, and means for automatically engaging said pivot member when the same has been lowered a predetermined distance with respect to the frame for locking said pivot member 110 with the frame to hold the brush elevated 115 above the ground.

ARTHUR A. ANDREWS.
